UNITED STATES PATENT OFFICE

168,112

MOTOR VEHICLE CAB

Theodore Ornas, Jr., Fort Wayne, Ind., assignor
to International Harvester Company, a corpo-
ration of New Jersey

Application August 5, 1952, Serial No. 20,895

Term of patent 14 years

(Cl. D14—3)

To all whom it may concern:

Be it known that I, Theodore Ornas, Jr., a citizen of the United States, residing at Fort Wayne, in the county of Allen and State of Indiana, have invented a new, original, and ornamental Design for a Motor Vehicle Cab, of which the following is a specification, reference being had to the accompanying drawings, forming part thereof, in which:

Figure 1 is a side elevational view of a motor vehicle cab showing my new design;

Figure 2 is a front elevational view of the vehicle cab;

Figure 3 is a perspective view taken from a point disposed rearwardly of the cab; and

Figure 4 is a perspective view taken from one side of the cab.

The dotted lines shown in the several drawing figures are for illustrative purposes only.

I claim:

The ornamental design for a motor vehicle cab, substantially as shown and described.

THEODORE ORNAS, JR.
